UNITED STATES PATENT OFFICE.

MARTIN MERK, OF BROOKLYN, NEW YORK.

FILE-CUTTING MACHINE.

SPECIFICATION forming part of Letters Patent No. 731,700, dated June 23, 1903.

Application filed September 12, 1902. Serial No. 123,146. (No model.)

To all whom it may concern:

Be it known that I, MARTIN MERK, a citizen of the United States of America, and a resident of Brooklyn, in the county of Kings, State of New York, have invented certain new and useful Improvements in File-Cutting Machines, of which the following is a specification.

This invention relates to certain new and useful improvements in machines for cutting files, in which a tool preferably formed with diagonal cutting edges has relative movement with respect to a blank, so that as the tool, for example, is drawn over said blank its diagonal cutting edges cut the teeth into the blank merely by being drawn over the blank under pressure. Examples of this tool and one way of using the same are shown in United States Patents Nos. 265,975 and 265,976.

In its preferred form my invention utilizes a tool-holder which permits the tool to slide therein during the process of cutting.

With this brief statement my invention may be said to consist in the improvement in file-cutting machines, as shown in its preferable embodiment in the accompanying drawings and as will now be hereinafter more particularly described, and then definitely set forth by the claims at the end hereof.

In the drawings accompanying and forming part of this application, Figure 1 is a side elevation of my machine. Fig. 2 is an end view of the same. Fig. 3 is a top plan. Fig. 4 is a perspective view of the tool-holder and vise for holding the tool. Fig. 5 is a horizontal section taken through the line *a* of Fig. 1. Fig. 6 is a detail which will be hereinafter more fully described. Fig. 7 is a side elevation of the tool-holder detached with parts broken away. Fig. 8 is a bottom plan of the tool. Fig. 9 is a detail sectional view of a portion of the vise with the blank-holder held therein and with a blank shown seated in the blank-holder.

Referring now to the details of the drawings by numerals, 1 indicates the main frame, provided, of course, with any style of supports or legs, and on the upper part of this frame is supported the bed or table 2, which may be secured in any desirable manner. Projecting upward from the aforesaid bed or

table 2 are standards or uprights 3 3, which are firmly secured to the bed or table by means of the nuts 4 4. These standards or uprights form the support for the tool-holder to be described. Slidingly supported on said standards is a frame 5, having extensions 6 6 at its ends on which are formed bosses 7 7, which fit over the standards and permit the frame to readily move up and down. Underneath the bosses I place collars 8 8 on the standards, which are capable of being adjusted by the set-screws 9. These collars are for the purpose of preventing the frame from being lowered too far under excessive pressure.

The frame 5 is provided with a recess 10, and on the under side of the frame is secured a removable plate or bar 11, which leaves a slot 12 between it and the bar 5 for the reception of a roller 13, which is held between the bifurcated ends of a hanger 14, to which is swiveled the tool-holder 16, the aforesaid roller 13 and the slot 12 permitting the tool-holder to be reciprocated back and forth within the limits of the said slot.

The tool-holder 16, which is shown best in Fig. 4, is of novel construction and comprises two downwardly-projecting frames 17 and 18, each of which is slotted or bifurcated, as shown at 19, and these slots are in alinement, as clearly shown. Above and below each of these slots are two antifriction-rollers 20 20, the journals of which are clearly seen in Fig. 4 and are numbered 21 21. These rollers are spaced just far enough apart in a vertical direction to permit the tool 22 to be passed between them, and the rollers permit said tool to slide with as little friction as possible.

Each of the frames 17 and 18 is also provided with a slot 23 on each side thereof, and in each of these slots is fitted an antifriction-roller 24, the pivots of which are vertical. These rollers, therefore, form a bearing for the vertical edge of the tool. It will thus be seen that the tool 22 is permitted freedom of longitudinal movement, and in its use, as hereinafter described, it may easily slide between its rollers. It will be evident that the bottom rollers are not absolutely necessary, as the weight of the parts, especially when in use, comes entirely on the upper side of the tool 22.

Underneath the tool-holder 16 is the blank-holder 25 and its vise, which latter consists of a bed-plate 26, secured to the bed or table 2, and two gripping-jaws 27 and 28, which have two sliding tongues 29, fitting grooves 30 in the bed-plate 26. A right and left hand threaded screw 32 passes through both of the gripping-jaws 27 and 28, by means of which the jaws may be moved toward or away from each other in order to secure or release the blank-holder. The outer ends of the screw 32 pass through supports 33, secured to the bed-plate 26, as clearly shown in Fig. 4. It follows from the construction just described that when the screw is turned in one direction the jaws may be moved toward each other and clamp the blank-holder in position, and when moved in the opposite direction the jaws are moved apart or separated, and the blank-holder may be thus released.

Before describing the mechanism for moving the tool-holder it might be well to first state that after the blank-holder has been clamped in the vise, as described, the tool-holder 16 is moved to the extreme end of its slot 12, with the tool projecting almost entirely out of one side of the tool-holder. If now the tool-holder is moved from one end of the slot to the other and at the same time sufficient weight is applied to said holder to keep the tool bearing very heavily on the blank, the tool will be caused to move through its rollers as it slides over the blank. This is caused by the fact that the tool is drawn over the blank at an angle thereto and because such tools are provided with their cutting edges at an angle to their length, as shown in Fig. 8. This form of tool, however, is common in the art, and my invention does not reside therein, but merely in the tool-holder and machine for using it. Instead of permitting the tool to slide through the tool-holder the tool may be clamped in position by set-screws 35, so that it is rigid therewith; but when the tool-holder is used in this manner the tool has to be held in the proper position to cut the blank without sliding. This is accomplished by arranging the tool-holder at such an angle that the tool moves bodily in direct line with its cutting edges.

It is obvious that the tool-holder and its tool may be drawn over the blank in any desired manner. It might even be drawn by hand or by a hand-lever; but I prefer that form of mechanism shown in the accompanying drawings, which I will now proceed to describe.

Each end of the tool-holder 16 is provided with a slot 36, in which is fitted and pivotally secured a connecting-rod 37, and these rods are passed between two of the standards 33 and are secured to jaws 38, projecting from each side of a head 39, and the latter is secured by a set-screw 40 to a reciprocating rod 41. The head 39 is made adjustable to permit it to be moved—for example, to the position shown in dotted lines in Fig. 3—for

the position of this head 39 controls the angle at which the tool and tool-holder are disposed relatively to the blank which is being cut. 70 This rod 41 extends vertically, but its lower end 42 is bent and extends horizontally under the bed or table 2 through bearings 43 and 44, cast onto the main frame 1, as clearly shown in Fig. 1. Connected to the horizontal member 42 of the reciprocating rod 41 is a downwardly-projecting arm 46, (see Fig. 6,) which is connected with the gearing for imparting motion to the moving parts. This gearing comprises a main shaft 50, to which motion is given by a pulley or belt-wheel 51, and on said shaft is a gear 52, meshing with a larger gear 53, (see Fig. 2,) secured to the side of a crank-wheel 54, both of which latter are journaled on the shaft 55, suitably supported in bearings projecting from the main frame 1. The crank-wheel 54 is provided with a wedge-shaped or dovetailed slot 56, in which is connected an adjustable slide 57, which carries a crank or wrist-pin 58. 90 A connecting-rod 60 connects this crank or wrist-pin 58 with the arm 46, hereinbefore described, so that when power is applied to the belt-wheel 51 it is transmitted through the two gears 52 and 53, the crank-wheel 54, its wrist-pin 58, and connecting-rod 60 to the arm 46, and the latter, with its connected parts, including the tool-holder and tool, is thus reciprocated back and forth.

In order to insure the proper amount of pressure being exerted by the tool upon the blank, I connect four rods 62 with the frame 5, and these rods extend downward beneath the bed or table 2 and are connected with a frame comprising a cross-bar 63 and two end bars 64, (see especially Fig. 1,) and said frame is connected by means of a link with a lever 66, fulcrumed in the main frame 1 at 67. One end of this lever is provided with a treadle 68, connected to it by a link 69. (See Figs. 1 and 3.) The shaft 67 is provided on its extreme end with a lever 70, on which is secured an adjustable weight 71. This weight, acting through its lever and shaft 67, draws downward on the link 65 and through the frame 63 64 65 and the rods 62 draws downward on the frame 5, and thus transmits downward pressure on the tool-holder and its tool. The pressure can of course be increased or diminished by changing the position of the weight on the lever 70, as will be evident. The purpose of the treadle 68 is to enable the operator to reverse the action caused by the weight, so as to elevate the tool-holder after a blank has been cut and permit of the removal of the cut file and the insertion of a new blank.

In some instances where a tapering file is being cut it is desirable to decrease the pressure of the tool in proportion to its taper. 130 To permit, or rather cause, this, I form an extension 72 on the arm 46, (see Fig. 1 and the perspective detail Fig. 6,) to which is connected a roller 73, which extends laterally

therefrom. Connecting the rod 62 is a bar 75, (see Figs. 1 and 5,) and to this bar is pivotally connected a wedge 76, provided with a set-screw or wing-nut 77 for holding the wedge in position. When a flat file is being cut, this wedge is not used; but when a tapering file is cut the wedge is lowered until it is set relatively to the roller 73 until it corresponds with the taper of the file. Then as the arm 46 is reciprocated the roller acting on the wedge causes the latter and the tool-holder through the bar 75 and the rods 62 to move upward to the extent of the depth of the wedge, thus releasing the pressure slightly.

15 It is believed the operation of my machine will be manifest to those skilled in the art, yet it might be said that the operation of cutting is as follows: The operator first depresses the treadle 68 with his foot, which raises the 20 tool-holder, and then inserts a blank-holder in the vise, securely fastening the same. The tool-holder is then moved to the beginning of its stroke with the tool in its proper position, the treadle released so as to permit the weight 25 to cause the tool to descend and bear with considerable pressure on the blank, and power is then applied. The motion from the belt-wheel being transmitted through the gearing, connecting-rod, and arm 46 to the reciprocating rod 41 this rod and its tool-holder are caused to reciprocate until the tool has completed its stroke, when the file is cut. As before explained, the tool is held at an 30 angle to the blank, and as its cutting lines or edges are in a diagonal or angular line the tool is drawn between its rollers as it moves over the blank, and thus the latter is cut for 35 its entire length.

I am of course aware that quite a number 40 of the features shown in my machine are old, and I do not therefore claim certain features. For instance, it is old to reciprocate a tool across a file to cut the same, as shown, for example, in Patents Nos. 265,975 and 265,976 45 to Nicholson, and I therefore do not claim such broadly. I believe I am the first, however, to permit the tool to receive its movement over the file-blank, partially at least, by slipping or rolling through a tool-holder. 50 While I have acknowledged the art to this extent, it is obvious that changes may be made in my machine without departing from my invention, and I therefore intend the following claims to cover all changes and modifications to which I am naturally entitled. 55 It is also manifest that my machine may be used for other purposes than for file-cutting.

What I claim as new is—

1. In a cutting-machine; a blank-holder; a 60 tool having cutting edges and a holder provided with means for slidably holding said tool; and means for reciprocating one of said holders with respect to the other; the said cutting edges lying oblique to the path of movement of the holder; substantially as described.

2. In a cutting-machine; a blank-holder; a

tool; a tool-holder provided with means for slidably holding said tool; said tool-holder being reciprocable across the blank; and 70 means whereby said tool is permitted a second movement transverse to the movement of the holder; substantially as described.

3. In a cutting-machine; a blank-holder; a 75 tool having cutting edges and a tool-holder provided with a recess or opening for receiving said tool; rollers permitting easy movement of the tool in the holder; and means for reciprocating one of said holders with respect to the other; the said cutting edges lying oblique to the path of movement of the holder and the said tool sliding through said rollers as one of said holders is reciprocated; substantially as described.

4. In a cutting-machine; a blank-holder; a 85 tool having cutting edges; a tool-holder having means for slidably holding said tool and means for reciprocating said tool-holder over said blank-holder; said tool sliding in its holder as said holder is reciprocated and the 90 cutting edges of said tool lying oblique to the path of movement of the tool; substantially as described.

5. In a cutting-machine; a tool-holder having two frames projecting therefrom, each 95 frame having an opening to receive a tool, a tool slidably held within said opening and having cutting edges; and means for reciprocating said tool-holder over said blank-holder; the said cutting edges lying oblique 100 to the path of movement of the holder; substantially as described.

6. In a cutting-machine; a bed or table having means thereon for holding a blank, a frame supported above said bed or table and 105 a tool-holder carried by said frame, said frame having a slot therein permitting the movement of said tool-holder; substantially as described.

7. In a cutting-machine; a bed or table having means for holding a blank; uprights projecting from said bed or table; a frame carried on said uprights; a tool-holder suspended from said frame and having means for slidably holding a tool; and means for reciprocating said tool-holder over said bed or table; 115 said tool sliding in its holder as the latter is reciprocated; substantially as described.

8. In a cutting-machine; a bed or table having means for supporting a blank; a frame supported above said bed or table; and a tool-holder carried by said frame and having longitudinal movement over said bed or table; 120 said tool-holder also having a swiveled connection with said frame; substantially as described.

9. In a cutting-machine; a bed or table having means for holding a blank thereon; uprights projecting from said bed or table; a frame movable on said uprights; a tool-holder 130 suspended from said frame and having means for slidably holding the tool; said tool-holder having a swiveled connection with said frame; and means for reciprocating the tool-holder

over said bed or table; substantially as described.

10. In a cutting-machine; a bed or table having means for supporting a blank thereon; uprights projecting from said bed or table; a frame movable on said uprights and having a slot or recess therein; a tool-holder having a swiveled connection with said frame, permitting the adjustment of said holder, means for adjusting said holder, said swiveled connection being movable in said slot or recess; and means for reciprocating said tool-holder; substantially as described.

11. In a cutting-machine; a bed or table having means for holding a blank; uprights projecting from said bed or table; a frame carried by said uprights; a tool-holder suspended from said frame and having a swiveled connection therewith; permitting the adjustment of said holder; means for adjusting said holder; and means for reciprocating said tool-holder comprising a head and a connecting-rod pivotally connecting said head and said tool-holder; substantially as described.

12. In a cutting-machine; a bed or table having a blank-holder; a frame carried over said bed or table and having a slot or recess therein; a tool-holder carried by said frame and having a part movable in said slot or recess; a tool slidingly held in said tool-holder and having cutting edges; and means for reciprocating said tool-holder; said cutting edges of said tool lying oblique to the path of movement of the holder; substantially as described.

13. In a cutting-machine, the combination of a bed or table having means thereon for holding a blank, a tool-holder and means for reciprocating the same, a connection with said holder passing beneath the bed or table, means for creating pressure on said holder; a pivoted wedge and means for adjusting the

same; and an element coacting with said connection under the bed or table and said wedge for relieving the pressure on said holder, substantially as described. 45

14. In a cutting-machine, the combination of a holder, means for reciprocating the holder, rods connected therewith and passing beneath the bed of the machine, a cross-frame connecting said rods, a weight for causing downward pressure on said parts, and a treadle for releasing said parts from pressure, a pivoted wedge for gradually relieving the pressure, and means for holding said wedge in position, substantially as described. 55

15. In a cutting-machine, the combination of a holder, means for reciprocating the holder, rods connected thereto, means for connecting said rods, a pivoted wedge and an adjusting device therefor, and an element movable with the holder and having a roller coacting with said pivoted wedge to relieve the pressure of the holder, substantially as described. 60

16. In a cutting-machine, the combination of a holder, means for reciprocating the holder, rods connected therewith and passing beneath the bed of the machine, a cross-frame connecting said rods, a weight for causing downward pressure on said parts, a treadle for releasing the parts from the pressure of the weight, an element as the arm 46 movable with the holder, a pivoted wedge coacting with said element to gradually relieve the pressure of the weight as the holder is reciprocated, and a device for holding said wedge in position, substantially as described. 70 75

Signed by me at Brooklyn this 3d day of September, 1902.
